UNITED STATES PATENT OFFICE.

JOHN F. BOETTNER, OF WATSON, MISSOURI.

HORIZONTAL WINDMILL.

1,334,882.

Specification of Letters Patent. Patented Mar. 23, 1920

Application filed February 26, 1917. Serial No. 151,115.

To all whom it may concern:

Be it known that I, JOHN F. BOETTNER, a citizen of the United States, residing at Watson, in the county of Atchison and 5 State of Missouri, have invented new and useful Improvements in Horizontal Windmills, of which the following is a specification.

The present invention comprehends generally improvements in that class of inventions known as air motors and more particularly relates to a wind mill.

It is the principal aim and object of the present invention to provide a device of 15 the above mentioned character designed to be disposed so as to rotate in a horizontal plane while the blades are of a construction to insure of a rotatable movement of the device regardless of the direction the wind 20 is blowing.

More particularly the present invention contemplates the provision of a device of the above mentioned character constructed in the form of a wheel comprising generally 25 a hub, radially disposed spokes and blades mounted on the spokes and connected to each other in circular series, the blades being shaped so that the wind will strike them regardless of the direction in which it 30 is blowing for rotating the wheel counter-clockwise while acting in conjunction with the spokes is a fastening means for insuring of the maintenance of the circular series 35 of blades concentrically of the shaft.

It is a more specific object of this invention to provide a device of the above mentioned character wherein means is employed for bracing the blades; to also construct the blades so that those which are not engaged 40 by the spokes will act as a means for bracing the others.

Among the other aims and objects of this invention may be recited the provision of a device of the character described with a 45 view to compactness, and in which the number of parts are few, the construction simple, the cost of production low and the efficiency high.

Other improvements and novel details in 50 the construction and arrangement of the various parts of the apparatus will be brought out more in detail in the description to follow, which for a clear understanding of the invention should be considered 55 in connection with the accompanying draw-

ings forming a part hereof, and wherein is disclosed for the purpose of illustration a convenient and satisfactory embodiment of the invention. It is to be noted in this connection that minor changes in the construction and arrangement of parts may be made without departing from the principle of operation of the various parts.

The invention is clearly illustrated in the accompanying drawings, in which:

Figure 1 is a top plan view of the device.

Fig. 2 is a side elevation thereof, and

Fig. 3 is a perspective view of one of the blades.

Similar characters of reference are employed in all of the above described views, to indicate corresponding parts.

Referring now, more particularly, to the accompanying drawings there is provided a shaft 1 on which is rotatably mounted the 75 improved wind wheel comprising generally a hub 2 from which radiate spokes 3 the outer ends of which support a circular series of blades 4. In the present instance each blade is formed from a single piece of sheet 80 metal and comprises a body 5 arcuate in cross section from the inner end of which projects an inwardly extending attaching flange 6 having openings 7 therein, for a purpose that will presently appear. Each 85 blade is reinforced by means of an arcuate angle strip 8 which conforms to the inner surface of the body and the flange and is rigidly secured thereto approximately medially of the upper and lower edges of each 90 blade. In connecting the blades to the spokes, certain of the blades and the adjacent brace strips 8 are formed with central openings 9 to permit of the disposition of the blades over the threaded outer end portion 10 of the spokes 3. The remaining 95 blades are now positioned so that the blades are all positioned in circular series or in such a manner that the attaching flanges 6 contact with the rear face of the adjacent blade 11 while suitable nut and bolt arrangements 100 are employed for engagement through the openings 7 and other openings 12 in the body portion 5 of the blades for retaining all of the blades in rigid engagement with respect 105 to each other and also in circular series as indicated in the drawings. By the peculiar construction of and the means for connecting the blades together the outer curved portions 5 of the blades will be positioned so as 110

to be struck by the wind regardless of the direction in which the wind is blowing for insuring of the counter-clockwise rotation of the wind wheel.

- 5 To insure the maintenance of the circular series of blades concentrically on the shaft, nuts 13 are employed and are adjustably engaged on the outer threaded portions 10 of the spokes and are designed to be adjusted so as to bear against the outer faces of the blades for holding the blades against movement consequently insuring of a well balanced wheel.

It is believed in view of the foregoing description that a further detailed description of the operation of the invention is entirely unnecessary. Likewise it is believed that the advantages of the invention will be readily apparent. However, it is to be observed in view of the particular combination and arrangement of parts that a rotation of the wheel in a counter-clockwise direction will be effected regardless of the direction in which the wind is blowing.

What is claimed is:

A device of the character described including a hub, a plurality of spokes radiating therefrom and having their outer portions threaded, a plurality of blades each being formed from a single piece of sheet metal including a body arcuate in cross section and an attaching flange projecting at an angle from the inner end of the body, angle bracing strips secured to the front face of each blade and conforming to the contour of the body and the flange, nut and bolt arrangements for rigidly connecting the body of one blade to the attaching flange of the adjacent blade, the body of certain of the blades and the adjacent bracing strip being formed with an opening for permitting of the disposition of the said blade about the end portion of the adjacent spoke, and nuts adjustably mounted on the threaded extremities of the spokes for insuring of the maintenance of the circular series of blades concentrically of the hub.

JOHN F. BOETTNER.
